UNITED STATES PATENT OFFICE.

WILLIAM H. McLAUGHLIN, OF HARTFORD, CONNECTICUT, ASSIGNOR TO CASSIUS S. CHASE, OF HARTFORD, CONNECTICUT.

CONNECTING DEVICE.

1,260,418.

Specification of Letters Patent. Patented Mar. 26, 1918.

Application filed June 21, 1917. Serial No. 176,181.

To all whom it may concern:

Be it known that I, WILLIAM H. McLAUGHLIN, a citizen of the United States, residing at Hartford, in the county of Hartford and State of Connecticut, have invented 5 certain new and useful Improvements in Connecting Devices, of which the following is a specification.

This invention relates to chain link connectors or fasteners intended by applicant more particularly for use with anti-skid chains, of the fixed point type, for automobile trucks. However, the invention is not at all limited to this use, but is capable of 10 use to advantage in a great many ways in many different arts. As shown in the first figure of the drawing, it is used to connect the terminal links of an anti-skid chain, as above mentioned. However, it may be used 15 just as easily to connect the terminal links of two or more chains.

The primary object of this invention is to provide means, movable with relation to each other and their casing, to receive and 20 hold chain links and the like against disengagement therefrom. Other objects are, to provide a casing in which said parts move and by which they are held, braced and guided; to provide for the locking of said 25 means in closed position; to provide for expeditious, easy and cheap repair or replacement of parts; to increase durability and simplicity and secure compactness, while at the same time decreasing the cost 30 of manufacture, all of which objects, among others, are accomplished by the combination, construction and arrangement of parts, all as hereinafter more particularly set forth, described and claimed.

40 In the accompanying drawings:

Figure 1 represents a central longitudinal sectional view of a device embodying my invention, the blocks and hooks being in side elevation, as applied to the felly of 45 a wheel, also shown in section, the ends of an anti-skid chain being applied to the hooks or projections, which are closed;

Fig. 2, a similar view of the connector alone, the hooks being in open or separated 50 position;

Fig. 3, a detail perspective view of all the parts separated; and

Fig. 4, a detail plan view, broken away, showing a modified form of the means for locking the blocks.

55

Referring now in detail to the drawings, A indicates the anti-skidding chain having its terminal links passed over the hooks 8, B the solid rubber tire and C the felly of the wheel to which the connector may be 60 attached and will be attached in the use contemplated by applicant.

The casing of the device is composed of a recessed front plate or cap 1 having parallel inner side faces and parallel inner end 65 faces which are at right angles to the inner face of its front wall, which face is parallel to the inner face of the base plate 2. It is important that all of said faces be straight and smooth to engage at all points and 70 brace and guide the blocks 7 hereinafter described.

Both the front plate 1 and base plate 2 are the same in outline, of the same size and provided with two lateral lugs 3, one 75 on each end, and on opposite sides, of the plates. These lugs 3 are provided with perforations 4 to receive fastening bolts 5, which, passing through the perforations in the lugs of both plates and into the felly 80 or other object on which the device is mounted, firmly hold the plates 1 and 2 together and the device as a whole on the felly or other object.

The front wall of plate 1 is provided with 85 a central longitudinal slot 6. The recess of this plate is just wide enough and just deep enough to receive the blocks 7 snugly, the rear faces of these plates 7 lying flush with the edges of said recess while their front 90 faces are in engagement at all points with the inner face of plate 1 and their side faces are in engagement with the side walls of said recess. Further, this recess will be slightly longer than the combined length of 95 said blocks 7 in order that said blocks may have longitudinal movement therein.

These blocks 7 are provided with hooks or projections 8, which may be integral with said blocks as shown, and are to be made 100

standard in shape and size, both as to block and hook, so that all such blocks and hooks will be identical in shape and size and may therefore be readily interchanged. Of course 5 for applicant's intended use two or three standard sizes of hooks, plates and casings may be made, in which case all hooks and blocks within one of those sizes would be made so as to be interchangeable.

10 When assembled the blocks 7 will fit snugly in the recess of the front plate 1 with their hooks 8 presented toward each other and projecting through the slot 6 of said plate.

15 It is to be noted that the distance between the ends of slot 6 and the respective end walls of the recess corresponds to the distance between the outer ends of the blocks 7 and the outer sides of their respective hooks 20 or projections 8, in order that, in locked position, the block indirectly acted on by the locking means may engage the wall of the end of said slot and the end wall of the recess and be firmly braced thereby, as well 25 as on all other faces.

To lock these blocks 7 in place I provide a locking thumb-screw 9 working through internally screw-threaded bore 10 in the center of one of the ends of the front plate 30 1, the inner end of this screw 9 engaging the outer end of the adjacent block 7 to force it over until its inner face and the end of its hook, which lie in the same transverse plane taken at right angles to the face of 35 the block, are in engagement with the inner face of the other block 7 and its hook 8 when the latter block and its hook are in engagement with the adjacent end wall of the recess and the adjacent end wall of the 40 slot 6 respectively.

In operation, the locking means will be moved out of locking position to release the blocks for longitudinal movement, one of the blocks 7 will be moved away from the other, as shown in Fig. 2, the chain links 45 passed over the ends of the hooks 8, then the blocks will be moved back so that their inner faces and the ends of their hooks 8 engage when the block away from the locking means is in engagement with the end wall of the recess and its hook is in engagement with the adjacent end wall of the slot 6, and the locking means will then be actuated to lock them in this position, 50 or the locking means may be used to force the blocks into this position, thus taking up any slack in the chain or chains.

In case one of the hooks is broken the 55 bolts 5 are to be removed, a new block 7 carrying a hook 8 inserted and the bolts replaced. In practice, because of the construction of the particular object on which the device as a whole is mounted, it may be found that the removal of one bolt 5 and 60 the loosening of the other will allow the de-

vice to be turned on the remaining bolt 5 as a pivot to a point where the two plates may be separated by turning one a little more on the remaining bolt 5 than the other, and access to the interior of the casing gained and 70 a new block 7 inserted in this way, without the necessity for complete removal.

Of course, where the device is applied to a smooth flat metal surface the latter may 75 take the place of the base-plate 2, which may then be dispensed with.

In the modification shown in Fig. 4 a cam 11, mounted on a pivot 12 in the end of the plate 1 and having its outer face flush with the outer face of the end of the plate 1 in 80 locking position, is used as a locking and releasing means instead of the thumb-screw 9 used in the preferred form. Otherwise the construction and operation is the same in both forms.

85 All parts are to be of reasonably heavy rigid nonresilient metal to prevent canting of the blocks 7, which, with their hooks 8, will preferably be of forged steel in order to withstand the great strain put upon them 90 in the use to which applicant intends to apply them.

Obviously, this invention may be embodied 95 in a number of forms, each varying in minor ways from the forms above described. Therefore, it is my intention to cover all such modifications in the appended claims which it is my desire shall be given the broadest construction consistent with their wording.

100 Having thus described my invention, what I claim as new and desire to secure by Letters Patent is:

1. A connecting device comprising a longitudinally slotted plate, in combination with plates adapted to move longitudinally of said slotted plate and having hooks projecting through said slot, means for guiding said movable plates and means for engaging the end of one of said movable plates for 110 locking said movable plates in position.

2. A connecting device comprising a longitudinally slotted recessed plate, in combination with plates adapted to move in said recess and guided and braced thereby and having hooks projecting through said slot, and means working through the end of said plate to engage one of said movable plates to lock the latter in position.

3. A connecting device comprising a longitudinally slotted recessed plate and a base plate, in combination with plates adapted to move in said recess, engaging in such movement and at rest the front and side walls of said recess and the inner wall of 125 said base plate, and having hooks projecting through said slot, and means working through said slotted plate to engage one of said plates to lock said plates in position.

4. A connecting device consisting of a lon-

itudinally slotted recessed plate and a base plate, in combination with plates adapted to move in said recess and having hooks projecting through said slot, means for securing said plates firmly together and means working through one of said plates to engage one of said movable plates to lock the latter in position.

5. A connecting device consisting of a longitudinal slotted recessed plate and a base plate, in combination with plates adapted to move in said recess and having hooks projecting through said slot, means passing through said recessed plate and said base 15 plate to hold them together and in position on some object and means working through

one of the latter plates to engage one of said movable plates to hold the latter in position.

6. A connecting device comprising a plate, in combination with independently mounted plates adapted to move bodily with relation thereto and to each other, and means for locking said plates in normal position.

In testimony whereof, I have signed my name to this specification in the presence of two subscribing witnesses.

WILLIAM H. McLAUGHLIN.
